United States Patent Office

Des. 190,225
Patented May 2, 1961

190,225

AUTOMOBILE

Leopold E. Garcia, P.O. Box 111, Bernalillo, N. Mex.

Filed June 24, 1960, Ser. No. 61,100

Term of patent 14 years

(Cl. D14—3)

Ex-1.

III. 2.

III. 2.

Fig. 1 is a perspective view of the front and side portions of the automobile, showing my new design;

Fig. 2 is a front elevation thereof;

Fig. 3 is a rear elevation thereof;

Fig. 4 is a right side elevation with the front closed; and

Fig. 5 is a left side elevation showing my new design with the front open.

I claim:

The ornamental design for an automobile, as shown.
